MOTOR CONTROLLING APPARATUS

Filed June 11, 1928

UNITED STATES PATENT OFFICE.

NORVAL E. BAKER, OF BLUE ISLAND, ILLINOIS, ASSIGNOR TO THE UNION SWITCH & SIGNAL COMPANY, OF SWISSVALE, PENNSYLVANIA, A CORPORATION OF PENNSYLVANIA.

MOTOR-CONTROLLING APPARATUS.

Application filed June 11, 1928. Serial No. 284,329.

My invention relates to motor controlling apparatus and particularly to apparatus for controlling a motor from a remote point. Apparatus embodying my invention is particularly adapted for, though in no way limited to, use in railway braking systems comprising a braking bar located in the trackway and actuated by a motor controlled from a distant point.

10 I will describe one form of motor controlling apparatus embodying my invention, and will then point out the novel features thereof in claims.

The accompanying drawing is a view, partly diagrammatic, illustrating one form of railway braking system including motor controlling apparatus embodying my invention.

15 Referring to the drawing, the reference characters 1 and 1^a designate the track rails of a stretch of railway track. Located on opposite sides of rail 1 and extending parallel therewith are two braking bars 2 and 3. Similar braking bars 2^a and 3^a extend parallel with rail 1^a on opposite sides thereof.

20 The braking bars 2, 3, 2^a and 3^a are operated by a motor, which as here shown is of the fluid pressure type and comprises a cylinder A containing a reciprocable piston 14 to which is attached a piston rod 13. The braking bars are 25 operatively connected with the piston rod 13 through suitable linkwork including a bell crank 5 and a lever 4 pivoted at point 4^a. When piston 14 moves to the left each braking bar is moved toward the associated rail 30 into its braking position in which it engages the side of a wheel of a railway vehicle traversing the rails 1 and 1^a. When the piston 14 moves to the right, however, into the position in which it is illustrated in the drawing, the 35 braking bars are moved away from the associated rails out of engagement with the wheels of a passing vehicle and the bars then occupy their non-braking positions.

40 The supply of fluid pressure, usually compressed air, to the cylinder A is controlled by main air valves 27, 30, 33 and 35, which main valves are in turn controlled by three electromagnetic pilot valves R, P and N. Each of these pilot valves comprises a valve body 18 having a valve stem 19 therein controlled by a magnet designated by the reference character 45 17 with a suitable distinguishing exponent. The valve stem 19 is biased to its upper or normal position by a spring 20 and when in such

position connects the associated pipe 22 with 55 atmosphere through a port 21. When magnet 17 is energized the stem 19 moves downwardly against the bias exerted by spring 20, to its reverse position, and the associated pipe 22 is then disconnected from atmosphere and 60 is connected with a source of fluid pressure, not shown in the drawing, through pipe 38.

The main air valves are located in a valve body 39. This body contains a cylinder having a reciprocable piston 24 therein. The upper side of this piston is subjected to the pressure in pipe 22 from valve R. Carried by piston 24 is the main valve 27 biased to its upper or normal position by spring 28. When valve 65 R is de-energized, piston 24 and valve 27 are in 70 their upper positions and port 37 is disconnected from port 25 and pipe 15 leading to the right-hand end of cylinder A. If, however, pilot valve R is energized, valve 27 is opened 75 so that fluid flows from pipe 38, through port 37, valve 27, port 25, and pipe 15 to cylinder A, thereby driving piston 14 to the left and forcing the braking bars toward the rails.

Valve body 39 also contains a piston 29 which is controlled by valve P. Piston 29 in 80 turn controls the main air valve 30 adapted to at times connect port 25 with atmosphere through port 31. When valve P is de-energized and valve 27 is closed, piston 29 and 85 valve 30 move into their lower positions in which they are shown in the drawing, under the influence of gravity. When valve 27 is open, however, fluid pressure in port 25 will raise valve 30, allowing this fluid pressure to 90 exhaust to atmosphere through port 31 unless valve P is energized. When valve P is energized, the upper side of piston 29 is exposed to the pressure in the associated pipe 22. Since the area of piston 29 is greater than that 95 of valve 30, the valve 30 will then be held in its lower position even if valve 27 is open, and communication between ports 25 and 31 will thus be interrupted.

In similar manner valve N controls the pressure applied to the upper side of piston 32 100 reciprocable in valve body 39 and controlling the two main air valves 33 and 35. A spring 36 biases the piston 32 and the valves controlled thereby to their upper positions in which pipe 16 leading to the left-hand end of the cylinder A is connected with atmosphere through port 40, valve 33 and port 34. When valve N is energized, pressure from pipe 22 105

forces piston 32 downwardly closing valve 33 and opening valve 35, thus supplying fluid pressure to the left-hand end of cylinder A through port 37, valve 35, port 40 and pipe 16.

5 The pilot valves R, P and N are controlled by a series of pressure responsive devices D, E and F each comprising a Bourdon tube 12 communicating with the right-hand end of cylinder A through a pipe 6. Each Bourdon 10 tube 12 controls a contact arm 7 which engages one of the associated fixed contacts 7^a or 7^b according to the pressure in the cylinder. The devices D, E and F are adjusted to operate upon different pressures so that as 15 the pressure in the cylinder increases these devices operate successively. When no pressure exists in the right-hand end of cylinder A, all contacts 7—7^a are closed. When the pressure in the cylinder reaches a predetermined 20 low value, such for example, as 25 lbs. per square inch, contact 7—7^a of device D opens. When the pressure exceeds this value, contact 7—7^b of device D is closed. In similar manner devices E and F operate as the 25 pressure reaches and exceeds certain higher values such for example as 60 and 75 lbs. per square inch, respectively.

The magnet 17^P of pilot valve R may be controlled by contact 7—7^a of any one of 30 the devices D, E, or F, depending upon the position of a selector designated by the reference character H. The selector H may be located at a point remote from the braking apparatus, as in the control cabin of a classification yard car retarder system, and in the form here shown, comprises a manually operable lever 8 adapted to engage any one of several fixed contacts 10^N, 10^P, 10^E, 10^F or 10^R. The selector H also comprises a segment contact 10^P so disposed that when lever 8 engages any one of the contacts 10^P, 10^E, 10^F, or 10^R, the lever also engages the segment contact 10^P, but that lever 8 does not engage segment 10^P when contact 8—10^N is closed.

45 Magnet 17^P is controlled in part by a relay G which is in turn controlled by a selected one of the devices D, E or F, depending upon the position of selector H, as will appear hereinafter.

50 The selector H controls the supply of energy to magnets 17^R, 17^P, and 17^N, from a source of energy such as a battery 51 having one terminal constantly connected with one terminal of each of the magnets through a wire 54. The other terminal of battery 51 is connected with lever 8.

As shown in the drawing, all contacts of 60 the selector H are open, and all valves R, P and N are de-energized, so that valves 27 and 35 are closed and valve 33 is open. Valve 30 is closed due to the weight of piston 29. Piston 14 of motor A occupies its right-hand position, and the braking bars are retracted to their non-braking positions. The supply 65 of pressure to both ends of the motor A is

interrupted and contacts 7—7^a of all devices D, E and F are closed. Relay G is de-energized. I will now assume that the operator actuates selector H to close contact 8—10^P. Current then flows from battery 51, 70 through contact 8—10^P, wire 57, contact 7—7^a of device D, wires 58 and 59, magnet 17^R of pilot valve R, and wire 54 back to battery 51. At the same time, current flows from battery 51 through contact 8—10^P, wire 65, back contact 66 of relay G, wire 67, magnet 17^P of valve P, and wire 54 back to battery 51. Valves R and P are both energized, therefore, 75 so that valve 30 is held closed, and valve 27 is opened to admit fluid pressure through pipe 15 to the right-hand end of motor A. The braking bars are therefore moved to their braking positions. When the pressure in the motor reaches 25 pounds per square inch, contact 7—7^a of device D opens, interrupting 80 the circuit for magnet 17^R, and allowing valve 27 to close. Valve 30 remains closed however so that the pressure is maintained in the motor. If the pressure in the motor becomes greater than 25 lbs. per square inch, contact 7—7^b of device D will close, and current from 85 battery 51 will flow through contact 8—10^P, wire 57, contact 7—7^b, wires 47 and 48, winding of relay G, and wire 54 back to battery 51. Relay G will then become energized, 90 opening, at back contact 66, the circuit for magnet 17^P. Valve 30 will then open to connect the right-hand end of motor A with atmosphere. When the pressure has been reduced to 25 lbs. per square inch, contact 7—7^b 95 of device D will open, and relay G will close to re-energize magnet 17^P. It will be seen, therefore, that when lever 8 is moved into engagement with contact 10^P, the pressure in the right-hand end of the cylinder is maintained at 25 lbs. per square inch.

In similar manner, if lever 8 is moved into engagement with contact 10^E, current flows from battery 51, through contact 8—10^E, wire 60, contact 7—7^a of device E, wires 61, 58 and 59, magnet 17^R, and wire 54 back to battery 51. Under these conditions contact 8—10^P is also closed so that magnet 17^P is energized over the circuit previously traced for that magnet, and the pressure in the motor is maintained at 50 lbs. per square inch. If the pressure exceeds this value, a circuit is closed for relay G from battery 51, over contact 8—10^E, wire 60, contact 7—7^b of device E, wires 49 and 48, winding of relay G, and wire 54 back to battery 51. Relay G therefore 110 opens back contact 66 to open valve 30 until the pressure drops to 50 lbs. per square inch. When contact 8—10^F of selector H is closed, the circuit for magnet 17^R is from battery 51, 115 through contact 8—10^F, wire 62, contact 7—7^a of device F, wires 63, 61, 58 and 59, magnet 17^R, and wire 54 back to battery 51. The pressure is then maintained at 75 lbs. per square inch, and if this value is exceeded, 120 125 130

current from battery 51 flows over contact 8-10^F, wire 62, contact 7-7^b of device F, wires 50, 49 and 48, winding of relay G, and wire 54 back to battery 51. As a result, magnet 17^P is de-energized and valve 30 opens to decrease the pressure in the motor to the value at which contact 7-7^b of device F opens. Finally, when contact 8-10^N is closed, current is supplied directly to magnet 17^R and the full fluid pressure existing in pipe 38 is then supplied to the motor.

If the operator wishes to restore the apparatus to its normal condition, he first moves the lever 8 to the position in which it is illustrated in the drawing, so that contact 8-10^P is open, thereby de-energizing magnets 17^P and 17^N, and allowing the fluid pressure in the right-hand end of cylinder A to exhaust to atmosphere through valve 30 and port 31. The operator then closes contact 8-10^N, thereby reversing valve N, and supplying fluid pressure to the left-hand end of cylinder A. The piston 14 then returns to its right-hand position and the braking bars are moved to their non-braking position. If the operator then opens contact 8-10^N, the consequent de-energization of magnet 17^N restores the apparatus to its normal condition by venting the left-hand end of cylinder A to atmosphere through valve 33 and port 34.

It should be particularly pointed out that if lever 8 is moved to a position corresponding to a lower pressure than that existing in cylinder A, relay G will immediately become energized to open valve 30. The pressure in the cylinder is then exhausted until the resultant pressure corresponds to the position which the lever then occupies. By this automatic pressure reduction, the apparatus always insures that the pressure in the cylinder exactly corresponds to the lever position.

Although I have herein shown and described only one form of motor controlling apparatus embodying my invention, it is understood that various changes and modifications may be made therein within the scope of the appended claims without departing from the spirit and scope of my invention.

Having thus described my invention, what I claim is:

1. In combination, a fluid pressure motor, a first magnet for controlling the admission of fluid to said motor, a second magnet for governing the exhaust of fluid from said motor, a relay at times controlled in accordance with the pressure in said motor, a manually operable lever, a circuit for said first magnet controlled by said lever, and a circuit for said second magnet controlled by said lever and by said relay.

2. In combination, a fluid pressure motor, a first magnet for controlling the admission of fluid to said motor, a second magnet for governing the exhaust of fluid from said motor, mechanism responsive to the pressure in

said motor, a manually operable lever, a relay controlled by said lever and by said mechanism, a circuit for said first magnet controlled by said lever and by said mechanism, and a circuit for said second magnet controlled by 70 said lever and by said relay.

3. In combination, a fluid pressure motor, a first magnet for controlling the admission of fluid to said motor, a second magnet for governing the exhaust of fluid from said motor, a plurality of contacts responsive to the pressure in said motor and arranged to operate at different values of said pressure, a manually operable lever, a plurality of circuits for said first magnet all controlled by 75 said lever and each controlled by a different one of said contacts, a relay, means for energizing said relay when any one of said circuits is closed and the pressure in the motor is above the operating value of the corresponding contact, and means for energizing said second magnet when any one of said circuits is closed provided said relay is de-energized.

4. In combination, a fluid pressure motor, 90 a first magnet for controlling the admission of fluid to said motor, a second magnet for governing the exhaust of fluid from said motor, a first contact arranged to be closed when and only when the pressure in said motor is below a certain value, a second contact arranged to be closed when and only when the pressure in the motor is above said certain value, a manually controlled contact, 100 a circuit for said first magnet, including said first contact and said manually controlled contact, a relay provided with a circuit including said second contact, and means for energizing said second magnet when said manually controlled contact is closed and 105 when said relay is de-energized.

5. In combination, a fluid pressure motor, 110 a first magnet for controlling the admission of fluid to said motor, a second magnet for governing the exhaust of fluid from said motor, a relay, manually controlled means for supplying current to said relay or to said first magnet according as the pressure in said motor is below or above a certain value, and a circuit for said second magnet controlled by said relay and by said manually controlled means.

6. In combination, a fluid pressure motor, 120 a first magnet for controlling the admission of fluid to said motor, a second magnet for governing the exhaust of fluid from said motor, a pressure responsive device having a first and a second contact arranged to be closed according as the pressure in said motor is above or below a certain value, respectively, a manually operable contact, a relay, a circuit for said first magnet including said first contact and said manually operable contact, a circuit for said relay including said second contact and said manually oper- 125

able contact, and means effective when said manually operable contact is closed and when said relay is de-energized to supply current to said second magnet.

5. 7. In combination, a fluid pressure motor, a first magnet for controlling the admission of fluid to said motor, a second magnet for governing the exhaust of fluid from said motor, a relay, a source of energy having one 10 terminal connected with one terminal of each of said magnets and with one terminal of said relay, a plurality of fixed contact members, a manually operable lever connected with the free terminals of said source and movable into engagement with a selected one 15 of said members, a plurality of fluid pressure responsive devices each operating to connect an associated one of said contact members with the free terminal of said relay or with the free terminal of said first magnet according 20 as the pressure in said motor is above or below a definite value which is different for

different devices, and means effective when said lever engages any one of said contact members and when said relay is energized to 25 supply current to said second magnet.

8. Railway braking apparatus comprising a braking bar located in the trackway, a fluid pressure motor for operating said bar, a first magnet for controlling the admission of fluid 30 to said motor, a second magnet for controlling the exhaust of fluid from the motor, a plurality of devices responsive to the fluid pressure in said motor, a manually operable lever, means for controlling said first magnet 35 by a selected one of said devices according to the position of said lever, a relay, means controlled by said lever for placing said relay under the control of the same device which is controlling said first magnet, and 40 a circuit for said second magnet controlled by said relay and by said lever.

In testimony whereof I affix my signature.

NORVAL E. BAKER.
